UNITED STATES PATENT OFFICE.

JASPER I. VAN VRANKEN, OF WINONA, MINNESOTA.

COIN-CARRIER PRINT PROTECTOR.

Application filed February 19, 1926. Serial No. 89,356.

This invention relates to the combination of a coin carrier with a print protector, especially for use by photographers who conduct a mail order business. In the past a coin carrier similar to a portion of petitioner's invention has been employed by such photographers as a container for coins mailed in with orders for kodak prints. Such a coin carrier is mailed to the customer usually with an order of kodak prints, for the purpose of furnishing the customer with a convenient coin carrier for use in making future orders. It may be noted that practically all of the photographers' mail order business is on a cash in advance basis, and the money for the order is sent in with the order. Heretofore, particularly since numerous photographers have been utilizing cloth bags as containers in mailing orders of prints, it has been necessary to use a print protector of sufficient rigidity to protect the prints from injury by reason of handling in the mails, and this has necessitated the use of a separate cardboard so folded that the prints are protected from damage in such handling, particularly the corners of the prints. It is an object of this invention to combine a coin carrier with a print protector, and thereby provide a means whereby one container will perform the service of what was formerly required of two containers, thus dispensing with the handling of a coin carrier and print protector separately.

It is a further object of the invention to provide a device which will accomplish the combined purpose of a coin carrier and a print protector in one piece of cardboard or similar material, which may be manufactured in one operation with much simpler machinery than would be necessary were coin carriers and print protectors both required as separate containers.

Another object of the invention is to provide such a device in which the coin will be well covered by several thicknesses of cardboard or other material, whereby the presence of the coin in the mailing package would be unknown to those handling mail.

These and other objects of the invention are fully set forth in the following description made with the accompanying drawings in which like reference characters refer to the same parts in the two different views, and in which

Fig. 1 is a plan view of the scored or

creased blank from which the preferred embodiment of my invention is constructed.

Fig. 2 is a fragmentary plan view of the upper portion of said blank with a portion thereof folded to form a coin pocket.

Fig. 3 is a plan view with some parts broken away of the device properly folded for mailing; and

Fig. 4 is a cross section taken on the line 4-4 of Fig. 3.

Referring more particularly to the drawings, I provide a substantially rectangular blank preferably constructed of cardboard pasteboard, or other material capable of being readily scored and folded, having the rectangular body portion 5 provided with a relatively large rectangular tongue 6 at one of the longitudinal sides thereof. Tongue 6 is preferably twice as long as it is wide, whereby the corners may be diagonally scored or creased on the lines 7, extending from the upper corners of body portion 5 to the mid point on the outer longitudinal edge of said tongue. The upper longitudinal side of body portion 5 is creased or scored along the line 8, while relatively narrow flaps 9 extend from the sides of body portion 5, creased or scored along the lines 10 to permit folding thereof upon said body portion. A rectangular flap 11 extends from the lower longitudinal side of body portion 5 scored or creased upon the line 12 to permit folding thereof upon said body portion, and preferably on the outer sides of flaps 9.

In utilizing my device for mailing, the corners of rectangular tongue 6 are folded upon the lines 7 forming a triangular shaped coin pocket, as shown in Fig. 2. Since the longitudinal sides of tongue 6 are twice the length of the shorter sides the shorter sides will approximately register with the crease 8. When this coin pocket is formed a coin or coins x may then be inserted in the triangular pocket and the pocket may be then folded against the body portion 5 and the vertex or tip thereof inserted through a slot 5^a in body portion 5 disposed preferably parallel with the creases 8 and 12. This secures the coin pocket to the inner side of the body portion, the fold at 8 closing the pocket. Prints or other sheets of material may then be disposed over the coin pocket and the narrow flaps 9 folded inwardly to cover the edges thereof and retain the same. The bottom flap 11 is preferably folded last cover-

ing the flaps 9 and a substantial portion of the prints or sheets within, after which the package may be tied or inserted in a sack or envelope for mailing.

5 It will be seen that the flaps 9 and 11 when folded constitute an efficient protective envelope in combination with the body 5 and coin pocket and that, moreover, the coin ϖ will be covered on one side by the folded portions of tongue 6 and also body portion 5, and on the other side by the tongue 6 and the prints or sheets disposed on the outer side thereof, within the protective envelope. The coin, therefore, is not likely to be de-

15 tected in the mail, having several thicknesses of material disposed at either side thereof.

From the above description it will be seen that I have invented an extremely simple but highly efficient combined protective envelope and coin carrier, capable of being manufactured from a minimum amount of material at little expense. This mailing package requires less postage, complies with all postal requirements, and is a 20 very convenient and economical article for those engaged in a mail order business.

What is claimed, is:

A combined envelope and coin carrier constructed of sheet material comprising a substantially rectangular body portion, a substantially rectangular tongue extending

from one edge of said body portion and being of the full length of said body portion, but of less width, said tongue being provided with scores so that its corners may be folded inwardly along diagonal lines intersecting the central point of the free edge of said tongue, said corners when so folded forming a triangular coin pocket, said coin pocket being scored and being folded inwardly 40 against said body member, said body member having a slot therein extending substantially parallel to the free edge of said tongue to receive the tip of said coin pocket and lock the same with said body member, said coin pocket lying entirely within the area of said body member when so folded, relatively narrow flaps extending from the side edges of said body portion scored for folding inwardly to engage a flat article 45 disposed over said body portion and said coin pocket and a closing flap portion extending from the lower edge of said body portion scored for folding inwardly against said side flaps to retain said side flaps and form in combination therewith and with said body portion a protective envelope.
